UNITED STATES PATENT OFFICE.

WILLIAM F. BUTLER, OF HILLSIDE, NEW JERSEY, ASSIGNOR TO AMERICAN CAN COMPANY, OF NEW YORK, N. Y., A CORPORATION OF NEW JERSEY.

AUTOMATIC SHEET-FEEDING DEVICE.

Application filed October 20, 1923. Serial No. 669,825.

To all whom it may concern:

Be it known that I, WILLIAM F. BUTLER, a citizen of the United States, residing in Hillside, in the county of Union and State of New Jersey, have invented a new and useful Improvement in Automatic Sheet-Feeding Devices, of which the following is a specification.

My invention relates to sheet feeding mechanisms and has more particular reference to mechanisms of the character particularly adapted for the feeding of metal sheets, such as tin plate and the like. While the invention will hereinafter be described as specially constructed for the feeding of sheets of tin plate to sheet cleaning, sheet oiling or sheet slitting mechanism, it will be readily manifest that it has valuable application in other connections both in its entirety and in the use of its individual and several features.

A principal object of the present invention is the provision of a sheet feeding mechanism which may be operated continuously and into which successive quantities of sheets may be inserted for feeding without in any way affecting the feeding action or necessitating its interruption, and the accomplishment as an additional important object of this advantage in a sheet feeding mechanism in which the sheets are stacked on edge and may be removed without the necessity of overcoming the considerable friction resultant from the motion of a bottommost sheet of a stack in which the sheets rest one upon the other.

Another important object of the invention is the provision of a sheet feeding mechanism of continuous operation which will require relatively light sheet separating and moving elements and which may be operated at high speed.

Another important object of the invention is the provision of a sheet feeding mechanism possessing these and other advantages and accomplishing these and other purposes of simple, sturdy construction and unlikely to require frequent repair, replacement or readjustment of its parts.

Numerous other objects and advantages of the invention will be apparent as it is better understood from the following description which taken in connection with the accompanying drawings discloses a preferred embodiment thereof.

Referring to the drawings,

Fig. 1 is a side elevation of a sheet feed looking from the right of the machine, the drive pulley and certain other parts being removed for clearer illustration.

Fig. 2 is a fragmental side elevation looking from the opposite side of the machine.

Fig. 3 is a top plan view thereof.

Fig. 4 is a longitudinal vertical section taken substantially on the line 4—4 of Fig. 3 and

Figs. 5, 6, and 7 are partial sectional views of the sheet separating mechanism taken similarly and on an enlarged scale.

Fig. 8 is a fragmental front view illustrating more in detail the sheet separating mechanism.

On the drawing reference character 11 represents a frame of any suitable form or construction adapted to support the operating portions, mechanisms and devices selected for the purpose of illustrating this invention. At the front a bracket 12 supports a stack holder composed of side bars 13 and bottom bars 14. The bars 13 and 14 may extend out and up at the slight incline shown in Fig. 1 as far as may be required and may be supported in any suitable fashion at their front or forward ends. The bars 14 are secured directly to cross member 15 of the bracket 12 as indicated at 16 and the bars 13 are secured by upstanding cleats or supports 17. The ends of the bars 14 are upturned as indicated at 18 to confine the lower edge of the rearmost sheet of the stack and through this sheet to combine the bottom of successive sheets in the stack.

In the present instance no means are provided for engaging the vertical side edges of the sheets of the stack and in order to prevent vertical buckling I prefer to give to the rearmost sheet and through it to the succeeding sheets a slight bend or bowed formation (seen best in Fig. 3) horizontally or transversely of the sheet. The upturned ends 18 of the bars 14 are given the angular arrangement shown to facilitate this horizontal bend as will presently be more fully explained. The sheets stand in the stack on edge and in upright or nearly vertical position. They are, however, inclined slightly toward the rear to insure them from falling forward in the stack.

Means are provided for removing the

rearmost sheet of the stack at each feeding action. In this action the top of each sheet as it is fed from the stack is first bent rearwardly and the next succeeding sheet engaged at or near the top to insure separation and the feeding of the sheets singly; thereafter the rear sheet is lifted and pulled away from the stack and then permitted to drop. The mechanism for accomplishing this separation and removal of the sheet from the stack will now be described.

The frame is provided with side uprights 21, which uprights form bearings for two shafts 22 and 23 each of which receives a characteristic oscillation as will be presently explained. The shaft 23 carries a pressure arm or member 24 adapted to bear upon the rear face of the rearmost sheet of the stack near but beneath the top and while in the drawings this arm is located at the center of the sheet transversely it will be understood that additional arms may be provided with corresponding arrangement and location.

25 A suction device comprising in the present instance a back 25 and two suction cups 26 is supported from the shaft 22. The back 25 is pivoted to an arm 27 in turn pivoted to a crank pin 28 upon a collar 29 fast on the shaft 22. In the operation of the sheet separating mechanism the top of the sheet is pulled away from the next adjacent sheet by the suction device and a member 41 having an operating finger 42 is thrust down back of the next adjacent sheet to confine its top edge against movement after the separation. The member 41 is pivoted on the pin 28 and has a tail 43 arranged between the shaft 23 and the guiding pin 44 carried by 40 the arm 24.

The upturned ends 18 of the bars 14 cooperate with the finger 42 to give a controlled bend to the rearmost sheet of the stack and through the rearmost sheet to the 45 succeeding sheets in sufficient amount to prevent the sheets from buckling or bending vertically. The arm 27 produces like action in cooperation with the ends 18 of the bars 14.

50 By reason of the characteristic movements of the shafts 22 and 23 the parts just described move in sequence and as follows. Fig. 7 shows the arrangement of the parts at the end of the feeding action and it will be noted that the finger 42 is pressing upon or against the rear of the stack. Thereafter the pressure member or arm 24 moves into the position shown in Fig. 5 as the initial movement in the next feeding operation. 55 The back 25 freely depends from its pivotal connection with the arm or link 27 and hangs in a pocket member 45 pivoted to the pivot pin connecting the back 25 and the link 27 and pivoted also at 47 to the arm 24. A stop or set screw 46 pushes the suc-

tion head 26 into contact with the rear of the rearmost sheet of the stack and above the point of contact between the arm 24 and this sheet. This is the position of the parts in Fig. 5. Thereafter movement of the shaft 70 causes the suction head to be tilted backwardly and away from the stack bending out the top of the sheet at the center portion of its top edge and the member 41 is moved down as shown to engage behind the next 75 adjacent sheet as shown in Fig. 6. Thereafter the parts move as will be readily understood into the position shown in Fig. 7.

Referring now to Fig. 3 reference character 51 indicates a main power shaft arranged beneath the top of the frame 11 and carrying a belt pulley 52. A cam 54 is mounted upon this shaft and this cam is engaged by a cam follower roll 55 operating within the cam groove 53 (Fig. 1) said roller being 80 mounted upon a pitman 56 having one end bifurcated at 57 to straddle the shaft 51 and the other end connected with an arm 58 fast on the end of shaft 22.

A cam 59 is arranged at the other or opposite end of the shaft 51 and is engaged by a follower roll 60 (Fig. 2) operating within the cam groove 61 of said cam 59 and said roll 60 is mounted upon a pitman 64 in turn connected with an arm 65 fast on shaft 23. 95

The suction or vacuum is created in the suction devices by an exhaust cylinder 71 mounted on an upright 21 and connected by a conduit 72 in part rigid and in part flexible with the suction heads. A plunger 73 is mounted in this cylinder and the plunger rod 74 is connected to a lever 75 carrying a follower roll 76 engaging a cam 77 (Figs. 3 and 4) on shaft 51, a spring 78 being provided to cause the follower to ride 100 properly upon the cam. A vent 62 is provided through the cylinder wall near its bottom, and the action of the cam is such that the plunger reaches the top of its stroke just before application of the suction is desired. During the upward stroke the plunger is driving the air in the cylinder out through the suction head. During the down stroke of the plunger the suction is applied until the plunger uncovers the port 110 62 which breaks the suction and releases the sheet.

The action of the parts is such that after separating the sheet the suction head lifts it to remove its lower edge from behind the 120 upturned ends 18 of the stack holder bars 14. The position of the sheet just before release is indicated in Fig. 7. When the suction is broken the sheet drops into a pocket 81 arranged therebeneath which limits its fall. 125 A wall 82 of this pocket is so arranged that the top edge of the sheet is brought into contact with or closely adjacent to a drum 83 on shaft 51. This drum or roll is provided with an electromagnet 84 at a point in 130

its surface and this magnet directs the upper edge of the sheet into a pass between it and cooperating friction means for mechanically advancing the sheet thereafter in the feeding movement. The cooperating friction means shown on the drawing consists of a plurality of pairs of rolls 85 mounted in pivoted bearing yokes 86 upon an idler shaft 87. These rolls normally bear on the face of the drum and in its continued rotation engage the sheet to insure its forward feed.

An electric current is supplied to the magnet 84 from wires 91 leading to brushes 92 of a contact ring 93, the faces of which are connected to the windings of the magnet and the arrangement is such that current is supplied to the magnet just before rotation of the drum brings the magnet up to adjacent the top edge of the sheet. Current is cut off from the magnet as soon as the magnet is about to depart from the sheet on its downward stroke.

25 The purpose of the magnet and drum arrangement is to arrange the sheets in precessional order and in the structure shown on the drawings to feed them edgewise and horizontal. To this end conveyor chains 101 taking over sprockets 102 let into the drum are provided.

30 It is thought that the invention and many of its attendant advantages will be understood from the foregoing description and it will be obvious that various changes may be made in the form, construction and arrangement of the parts without departing from the spirit or scope of the invention or sacrificing all of its advantages, the form hereinbefore described being merely a preferred embodiment thereof.

35

40 I claim:

1 claim.

1. In a sheet feeding mechanism the combination, of a stack holder for holding a stack of sheets in upright position and in bowed formation with their rear faces concave and with the sheets resting upon their lower edges, the rear of said stack being substantially open and said stack holder permitting the insertion of quantities of sheets in the front thereof, and means for successively withdrawing the sheets from the back of the stack and in an initial direction substantially at right angles to the plane of the individual sheet.

55 2. In a sheet feeding mechanism, the combination of a stack holder for holding a stack of sheets in upright position with the sheets resting upon their lower edges, the stack of sheets in said holder being open at the front for insertion of sheets and the back for their removal, and means for slightly bowing the sheets while in the stack in a horizontal direction to prevent vertical buckling of the sheets.

65 3. In a sheet feeding mechanism, the combination of a stack holder for holding

a stack of sheets in upright position with the sheets resting upon their lower edges, the stack of sheets in said holder being open at the front for insertion of sheets and the back for their removal, and a plurality of devices for alternately engaging the rear faces of the upper parts of the sheets while their side edges are left free, for producing a controlled bending of the sheet at the rear of the stack. 75 70

4. In a sheet feeding mechanism, the combination of a stack holder for holding a stack of sheets in upright position with the sheets resting upon their lower edges, the stack of sheets in said holder being open at the front for insertion of sheets and at the back for their removal, and means engaging the top and bottom of the sheet at the rear of the stack and at points distant from the side edges of the sheets and bending the sheet laterally to prevent vertical buckling.

5. In a sheet feeding mechanism, the combination of a stack holder for holding a stack of sheets in upright position with the sheets resting upon their lower edges, the stack of sheets in said holder being open at the front for insertion of sheets and the back for their removal, and the sheets being in bowed formation while they are in the stack, members engaging the bottoms of the sheets and members for engaging and individually withdrawing the tops of the sheet as they are presented for separation from the remainder of the stack. 90 95

6. In a sheet feeding mechanism, the combination of a stack holder for holding a stack of sheets in upright position with the sheets resting upon their lower edges, the stack of sheets in said holder being open at the front for insertion of sheets and the back for their removal, members engaging the bottoms of the sheets and members for engaging and individually withdrawing the tops of the sheet as they are presented for separation from the remainder of the stack, said last mentioned members being operable to lift the sheet out of engagement with said first mentioned members, and a finger movable towards and from the stack and also upward and downward.

7. In a sheet feeding mechanism, the combination of a stack holder adapted to support a stack of sheets in upright position and in bowed and rearwardly concave formation but inclined sufficiently towards the rear to maintain the sheets in contact, said stack holder being unobstructed at the sides, means for confining the bottom of the rear sheet of the stack and means separating the top of the rear sheet from the next adjacent sheet. 120 125

8. In a sheet feeding mechanism, the combination of a stack holder adapted to support a stack of sheets in upright position and in bowed and rearwardly concave for- 130

- mation but inclined sufficiently towards the rear to maintain the sheets in contact, said stack holder being unobstructed at the sides, means for confining the bottom of the rear sheet of the stack and means separating the top of the rear sheet from the next adjacent sheet, and acting thereafter to withdraw said rear sheet, and means acting, in advance of the withdrawing movement of said first mentioned means for temporarily confining the top of the next adjacent sheet.
9. In a sheet feeding mechanism, the combination of a stack holder adapted to contain a stack of sheets arranged on edge and means for withdrawing the rearmost sheet of the stack, said means including a finger member pressing upon the rearmost sheet near its top and a member acting thereabove to move the top edge of such sheet away from the stack, and means for moving said finger member towards and away from the stack.
10. In a sheet feeding mechanism, the combination of a stack holder adapted to contain a stack of sheets arranged on edge and means for withdrawing the rearmost sheet of the stack, said means including a member for pressing upon the rearmost sheet near its top, a member for pressing the rearmost sheet of the stack against the next adjacent sheet and a suction device engaging the rearmost sheet above said pressure member to pull the top of the sheet away from said next adjacent sheet, and means for moving said pressure member towards and from the stack.
11. In a sheet feeding mechanism, the combination of a stack holder adapted to contain a stack of sheets arranged on edge and means for withdrawing the rearmost sheets of the stack, said means including a member for pressing upon the rearmost sheet near its top, a member for pressing the rearmost sheet of the stack against the next adjacent sheet and a suction device engaging the rearmost sheet above said pressure member to pull the top of the sheet away from said next adjacent sheet, said pressure member and said suction device being movable away from the stack to carry the rearmost sheet to separated position, and means for moving said pressure member rearward and forward and also downward and upward.
12. In a sheet feeding mechanism, the combination of a stack holder for holding a stack of sheets in upright position, means moving the rearmost sheet of the stack laterally of its plane away from the stack and then permitting it to drop vertically, a member for engaging the lower edge of the sheet to limit the vertical fall and magnetic means gripping the upper edge of the sheet and directing it in a horizontal feeding movement.
13. In a sheet feeding mechanism, the combination of a stack holder for holding a stack of sheets in upright position, means moving the rearmost sheet of the stack laterally of its plane away from the stack and then permitting it to drop vertically, a member for engaging the lower edge of the sheet to limit the vertical fall, rollers for engaging the upper edge of the sheet and feeding it to a horizontal position and means directing the upper edge of said sheet between said rollers.
14. In a sheet feeding mechanism, the combination of a stack holder for holding a stack of sheets in upright position, means moving the rearmost sheet of the stack laterally of its plane away from the stack and then permitting it to drop vertically, a member for engaging the lower edge of the sheet to limit the vertical fall, rollers for engaging the upper edge of the sheet and feeding it to a horizontal position and means pulling the upper edge of said sheet between said rollers.
15. In a sheet feeding mechanism, the combination of a stack holder for holding a stack of sheets in upright position, means moving the rearmost sheet of the stack laterally of its plane away from the stack and then permitting it to drop vertically, a member for engaging the lower edge of the sheet to limit the vertical fall, rollers for engaging the upper edge of the sheet and feeding it to a horizontal position and means for directing said upper edge into said rollers.
16. In a sheet feeding mechanism, the combination of a stack holder for holding a stack of sheets in upright position, means moving the rearmost sheet of the stack laterally of its plane away from the stack and then permitting it to drop vertically, a member for engaging the lower edge of the sheet to limit the vertical fall, and magnetic means arranged to engage the under side of the sheet for moving the sheet into a horizontal feeding movement.

WILLIAM F. BUTLER.
